[57] CLAIM

The ornamental design for a capped pump dispenser, as shown and described.

DESCRIPTION

FIG. 1 is a right side elevational view of the capped pump dispenser showing my new design, the left side being a mirror image;

FIG. 2 is a fragmentary front elevational view thereof, with the cap omitted for clarity of illustration;

FIG. 3 is a top plan view thereof, again with the cap omitted for ease of illustration and the bottom being unornamented;

FIG. 4 is a right side elevational view of FIG. 3;

FIG. 5 is a top, front perspective view of FIG. 3; and,

FIG. 6 is a top, front perspective view of a second embodiment of the design of FIG. 1, with the cap omitted for ease of illustration and the only difference being in the configuration of the spout nozzle.
